UNITED STATES PATENT OFFICE.

JAMES H. REED, OF SWAMPSMOTT, MASSACHUSETTS, ASSIGNOR TO THE SINGER MANUFACTURING COMPANY, OF ELIZABETH, NEW JERSEY, A CORPORATION OF NEW JERSEY.

WELT-GUIDE AND STITCH-INDENTING MECHANISM.

Application filed September 9, 1920. Serial No. 409,189.

To all whom it may concern:

Be it known that I, JAMES H. REED, a citizen of the United States, residing at Swampscott, in the county of Essex and 5 State of Massachusetts, have invented certain new and useful Improvements in Welt-Guide and Stitch-Indenting Mechanism, of which the following is a specification, reference being had therein to the accompanying 10 drawings.

In making the so-called stitch down shoes, it has been customary to attach a welt strip in the crease between the upper and the sole, this strip and the sole holding between 15 them the outwardly turned margin of the shoe upper. This strip is sewed in place through the upper margin and the sole, and not only serves to strengthen the shoe, but also to improve its appearance. Some difficulty 20 has been experienced in properly placing the welt in this position, the welt tending to spring outwardly from the shoe upper leaving a space permitting the lodgment of dirt and foreign matter, and detracting from the appearance of the shoe. 25

This invention provides means which may be attached to a straight needle sewing machine, and by which the welt may be fed progressively into position closely engaging 30 the upper and be stitched in place.

A further feature of this invention relates to improved means for indenting the welt step by step between the stitches to add to the appearance of the finished shoe, 35 this means consisting of an indenting tool carried by the presser foot and slidable laterally of the line of feed into and out of the path of the needle.

For a more complete understanding of 40 this invention together with other objects and advantageous details and combination of parts, reference may be had to the accompanying drawings in which—

Fig. 1, is a fragmentary elevation, partly 45 broken away, of the head of a sewing machine equipped with this invention.

Fig. 2, is a side elevation, with parts in 50 section, of the forward portion of the machine.

Fig. 3, is a detail of the indenting tool actuating mechanism.

Fig. 4, is an elevation of a cam.

Fig. 5, is an elevation of the parts shown in Fig. 2, and

Fig. 6, is a plan of the same parts showing a portion of the shoe in position to be sewed. 55

A represents a portion of the machine head having an upwardly extending hollow standard B in which is journaled the main 60 operating shaft 1, and a lateral hollow work-supporting arm C forming a housing for the usual shuttle mechanism and on the upper surface of which the work to be stitched is held. Externally of the standard B the usual fly wheel 2 and belt pulley 3 are made fast to the shaft 1, this shaft being shown as provided with a crank at 4 for actuation of a connecting rod 5 projecting toward the base of the machine, and 65 by which the shuttle mechanism, not shown, is actuated. Adjacent the crank 4, and for a purpose to be later described, a cam 6 is fixed to the shaft 1, this cam being preferably made in halves screwed together in 70 position on the shaft as shown in Fig. 4, one of the screws being indicated in dotted line at 7. Cam 6 is in the form of a flat disc with a segmental cam surface member 8 screwed thereto at 9 and 9^a, as shown in Fig. 4, member 8 having inclined ends 10 and 10^a and a flat intermediate portion. As shown in Figs. 1 and 3, a vertically extending shaft 11 is journaled in lugs extending from the standard B, this shaft carrying at 75 its upper end a crank arm 12 terminating in a cam roll 13 positioned to be engaged by the cam segment 8. Between the supporting lugs in which shaft 11 is journaled, is mounted thereon a torsion coiled spring 14, 80 one end of which is made fast to one of the journal lugs and the other end made fast to a collar 15 fixed to shaft 11, this spring serving to urge the roll 13 into engagement with the cam 6. The lower end of shaft 11 has fixed thereto an arm 16 terminating in a ball 17. The ball 17 bears in a two part 85 ball socket 18 fixed to a rod 19 which extends outwardly through a slot 20 in the machine head above the arm C. 90

At 21 in Figs. 2 and 5, is shown a reciprocating needle bar carrying a straight eye needle 22, this needle reciprocating through a needle guide 23. These parts are mounted and driven in the usual manner by which piercing and retracting movement through the work and lateral motion while in the work to feed the same, and return motion 100

100

105

while out of the work is given the needle. At 25 is shown the presser foot having an elongated slot 26 therein, through which the needle moves both in piercing and reTRACTING from the work and also in feeding the same. Slot 26 terminates at one end in a portion 27 opening laterally thereof. Presser foot 25 is carried by the usual presser foot bar 28 and is actuated in the usual manner to engage the work tightly during the retracting and piercing movement of the needle, and to lift therefrom during the feed. The actuating mechanism for these parts have not been herein shown as they are old and well known in the art, and may be of any suitable or usual description.

The arm C carries a work plate D. Between the lugs 29 thereof is journaled a pin 30. A sleeve 31 is carried by the pin 30 between the lugs 29, and carries fixed thereto, a yoke member 32. A torsion spring 33 surrounds the extremity of the rod 30, outwardly of the bearing 29, being fixed at its inner end thereto and at its outer end to a head 34 of the pin 30, this spring tending to rotate the pin 30 in position to hold the outer end of the yoke 32 depressed. Yoke 32 is split at its rearward end and has lugs 35 and 37 integral with the opposite split portions, through which a tightening screw 36 passes and by which the sleeve is clamped to the pin 30. The outer end of the yoke 32 is perforated at 38 for the reception of the shank 39 of a welt guide 40, shank 39 being held in position by means of a screw 41. The guide 40 has a welt guide slot 42 extending downwardly and outwardly toward the needle by which a welt shown at W fed therethrough will be pushed outwardly from the work-supporting arm C and into close engagement with the crease between the upper and sole of the shoe being sewed, as shown in Fig. 6.

The presser foot 25 has a rearwardly extending perforated lug 43 in which is slidably mounted a guide pin 44. Extending in spaced parallel relation to pin 44 is an indenting member 45 slidably mounted in a groove 46 in the lower face of the presser foot in position to intersect the path of the needle 22 during its work piercing stroke. The rear end of the indenting member or tool 45 has an upwardly extending portion 47 by which it is fixed to a lug 48 integral with a block 49 to which the guide pin 44 is fast. The rear end of block 49 is bifurcated for a pivotal reception of an ear carried by a block 50 in which is made fast the forward end of the rod 19, above mentioned.

The operation of this mechanism is as follows:

A lasted shoe is presented in the position shown in Fig. 6 to the sewing instrumentalities

ties and a welt is fed through the welt guide 40 to lie on the upper surface of the outward margin of the shoe upper which is fast to the marginal portion of the sole. The presser foot is in position above the welt so that the welt, upper margin, and sole form the material to be stitched. On actuation of the machine, the sewing instrumentalities function in their usual manner to sew these three parts of the work together, the inclined position of the welt guide with relation to the line of feed crowding the welt closely into the crease between the upper and the sole. After the presser foot is raised to allow for the feed of the work, the cam segment 8 rides from contact with roll 13, allowing the spring 14 to turn shaft 11, and push rod 19 outwardly to project the indenting tool 45 across the needle path to substantially the full width of the welt. The clamping of the presser foot on the work during the retraction of the needle to the next stitch causes a lateral indentation to be made in the surface of the welt by the tool at the point where the needle will next descend. Before the needle reaches this point on its next piercing stroke, segment 8 has again engaged roll 13 and rocked shaft 11 to retract the tool from the needle path. This action of the tool causes the welt to be indented between the stitches as shown at a in Fig. 6, each indentation being made one stitch length ahead of the last complete stitch.

Having thus described one embodiment of this invention, though it is evident that many changes might be made therein without departing from its spirit or scope, what is claimed is,

1. In a sewing machine, sewing instrumentalities including a reciprocatory needle, means to present a welt to said instrumentalities to stitch the same, a welt indenting-tool effective to engage and indent the needle-entering face of the welt at a point coincident with the subsequent penetration of the welt by said needle, and means for retracting said welt indenting-tool from indenting position out of the path of said needle.

2. In a sewing machine, sewing instrumentalities, a welt guide forward of said instrumentalities in the line of feed in position to crowd the welt into the crease between the upper and sole of a shoe being sewed, a presser foot, and means carried by said presser foot and arranged to indent the upper face of said welt one stitch length in advance of the last complete stitch.

3. In a sewing machine having a work-support and a needle movable laterally to feed the work, a presser foot through which the needle passes, and an indenting tool movably mounted on said presser foot in line with the start of feed of said needle and

- confined against movement relatively to the presser-foot toward and from the work-support, and means for retracting said tool from the path of the needle prior to the 5 needle reaching that position.
4. In a sewing machine, a work-support, sewing instrumentalities, a presser foot, and an indenting tool slidably carried by said presser foot and confined against movement 10 relatively to the presser foot toward and from the work-support.
5. In a sewing machine, sewing instrumentalities, feeding mechanism, a presser foot, an indenting tool sustained in position 15 to indent the work one stitch length in advance of the last complete stitch, and means for reciprocating said tool transversely of the direction of feed.
6. In a sewing machine comprising sewing 20 instrumentalities including a needle movable laterally to feed the work, a presser foot adjacent the needle and provided with a transverse slideway rigidly connected therewith, and a drive shaft for actuating said instrumentalities, the combination 25 of a stitch indenting tool mounted in the slideway of said presser foot, and means actuated by said shaft for sliding said tool.
7. In a sewing machine comprising sewing 30 instrumentalities including a needle movable laterally to feed the work, a presser foot adjacent the needle and provided with a transverse slideway, and a drive shaft for actuating said instrumentalities, the combination 35 of a stitch indenting tool mounted in the slideway of said presser foot and arranged to be projected and retracted across the path of said needle, a cam on said shaft, and connections from said cam to said tool for projecting and retracting said tool. 40
8. In a sewing machine, the combination 45 with stitch-forming mechanism including a reciprocatory needle, of a stitch-indenting tool having a welt-engaging path of movement coincident with the path of the subsequent work-penetrating movement of said needle, and means for actuating said indenting-tool to form spaced indentations in the work.
9. In a sewing machine, the combination 50 with stitch-forming mechanism including a reciprocatory needle, of a welt-guide positioned to present a welt to the stitch-forming mechanism, an indenting tool arranged to engage the upper face of the work at a 55 point coincident with the subsequent penetration of the work by the needle, and means for retracting said indenting tool in a direction substantially transverse to the lead of the welt and the path of reciprocation of 60 the needle.

In testimony whereof I have signed my name to this specification.

JAMES H. REED.
